SUBMERGED SOAP DISPENSER

Edward B. Lawler, New York, N. Y.

Application July 23, 1940, Serial No. 346,925

3 Claims. (Cl. 45—28)

This invention relates to devices for feeding cleaning material in dish washing machines of the tank or spray type.

The principal object of this invention is to provide a feeder of cleaning material which is adapted to function while being submerged in a tank type dish washing machine, or operate in the wash tank of a spray type dish washing machine.

Another object of my invention is to provide a submerged soap feeder which is automatic in operation and adjustable at will and so constructed that it provides instantaneous soap feeding at the start and gradual or slow feeding when the tank is charged with cleaning material.

Another object of this invention is to provide a submerged soap feeder wherein the discharge of soap solution is controllable at will, the control being arranged so as to make it hard to get at thus supplying at all times a uniform solution of a predetermined strength.

A further object of this invention is to provide a soap feeder for dish washing machines having several compartments, a central covered and attached open pockets the latter adapted for easily filling without spilling on floor and adaptable for refilling during a temporary stoppage of the washing machine without removing the cover of the central compartment.

A further object of this invention is to provide a submerged soap feeder with openings and replaceable screens arranged over the openings.

Other objects and advantages will appear in the following description and will be pointed out in the appended claims.

The invention will be disclosed with reference to the accompanying drawing, in which—

Fig. 1 is an elevational view of my feeder in a tank type machine.

Fig. 2 is a plan view of the feeder.

Fig. 3 is a vertical view partly in section.

Fig. 4 is an enlarged view of the control.

Fig. 5 is an end view of my feeder.

Referring to the drawing the numeral 10, represents a dish washing machine of the tank type. Within the tank, at the bottom thereof, the soap feeder 11, is set.

The soap feeder 11, made of non-corrosive metal comprises a plurality of compartments, a center compartment 12, and wedge shaped end pockets 13, and 14, and cover 15.

The central compartment 12, is provided with a plurality of openings 16, on each side and the end pockets are provided with openings 17, and the cover 15, is provided with opening 18.

In order to prevent sludge or impurities filling the openings while the feeder is in the tank, I have provided a method of screening the openings as follows:

5 At the openings 16, and 17, I place slots 18', and 19, and insert therein screens 20, and 21. These screens are removable at will and can be replaced when damaged or when they become impervious due to clogging of the screen.

10 The opening 18, in the cover 15, is of a large size and in order to control the size of the opening I place a platen 19, which is revolvably arranged on a screw 20. This platen 19, has a series of openings 22, 23 of various sizes so that

15 when the platen is turned with the small opening opposite the opening 18, then the flow through the feeder is slow. By turning the platen any size opening may be obtained.

20 In order to prevent the tampering or accidental moving of platen, I have arranged openings 24—25 opposite the openings 22, 23 and by means of screw 26, any size opening can be fastened or locked into position.

25 In order to prevent any sludge over the opening 18, I have arranged a screen 27 fastened in a ring 28 which is adapted to be held over the opening 18, by means of screws 29, 30. The fastening of the screen affords a double protection against any tampering with the control platen 19.

30 The reason for making the end pockets 13, and 14, wedge shaped is as follows: When the feeder is to be used all the compartments are filled with soap and the feeder is inserted into the bottom of the tank. The initial charging is immediately begun and due to the open pockets the water is charged in a few minutes. The water is then continuously charged by the main or central compartment and the amount of soap solution obtained depends on the size of opening in control platen 19.

40 If the dish washing is completed and the feeder is removed it will be found that the end pockets are empty and the main or central compartment partly filled depending on the amount of dish washing completed.

45 In order to use the feeder for the next batch of dishes all that would be necessary is to refill the end pockets with new soap and insert the feeder into the tank.

50 Heretofore the end pockets were rectangular and narrow, and when refilling was tried most of the soap would fall to the floor and be wasted. With this improvement I have made the open end very large but the total volume of end pocket the same as the old rectangular pocket. This

facilitates filling the pockets without any loss and since it offers a larger flat surface to the water the soap will dissolve faster for the initial charge. The filling of the wedge shaped pockets is further facilitated by the wall 31, formed by the cover 15, over the central compartment. This wall prevents the soap from spreading.

What I claim is:

1. A soap feeder comprising a central rectangular receptacle having open top wedge-shaped receptacles formed on the ends thereof, said receptacles providing compartments for receiving soap, a cover for said central receptacle, a small opening in said cover and small openings in the outer side walls near the bottoms of the several compartments.

2. A soap feeder comprising a central rectangular receptacle having open top wedge-shaped

receptacles formed on the ends thereof, said receptacles providing compartments for receiving soap, said central receptacle projecting above said wedge shaped receptacles, a cover for said 8 rectangular receptacle, a small opening in said cover and small openings in the outer side walls near the bottoms of the several compartments.

3. A soap feeder comprising a central rectangular receptacle having open top wedge-shaped receptacles formed on the ends thereof, said receptacles providing compartments for receiving soap, a cover for said central receptacle, a small opening in said cover and small openings in the outer side walls near the bottoms of the several compartments and removable screens adjacent to said opening in the cover and adjacent to said openings near the bottom.

EDWARD B. LAWLER.
